UNITED STATES PATENT OFFICE.

EDWARD F. BESSEY, OF CHICAGO, ILLINOIS, ASSIGNOR TO HOWE AUTO PRODUCTS COMPANY, OF CHICAGO, ILLINOIS, A CORPORATION OF ILLINOIS.

IGNITION TIMER.

Application filed July 17, 1920. Serial No. 396,915.

To all whom it may concern:

Be it known that I, EDWARD F. BESSEY, a citizen of the United States, residing at Chicago, in the county of Cook and State of Illinois, have invented certain new and useful Improvements in Ignition Timers, of which the following is a specification.

This invention relates to ignition timers or circuit closers of the type employed for 10 periodically closing a circuit, as, for instance, the ignition circuit of an internal combustion engine, and has for its object to provide such a device that will be efficient and durable in use, particularly in the matter of maintaining contact of low resistance 15 to passage of the current, and which will be of simple and cheap construction.

The novel features of the invention reside primarily in the construction of the means 20 whereby traveling contact is maintained with the annular series of circuit terminals, such contact being in the form of a sliding shoe mounted upon the outer end of a sweep or radius arm, with such freedom of movement 25 as will adapt it to conform to the surface of the annulus over which it travels and against which it is constantly pressed by a suitable spring. The shoe in its preferred embodiment, while having a freely rocking 30 support on the arm, is fixed against relative rotation thereon in a manner to maintain alinement of the shoe with the annulus, and has an upturned end or ends that permit the shoe to ride smoothly along the track 35 provided by the annulus.

The invention will be more fully understood upon reference to the accompanying drawings, in which—

Figure 1 is an axial section; and Figure 2 40 an inner side elevation, partly in section, of a timer embodying the several features of the present invention.

Figures 3, 4, and 5 represent the contact device; Figure 3 being a perspective view 45 of the sweep or carrier for the sliding shoe; Figure 4 the blank from which the same is made; and Figure 5 a perspective view of the slide shoe; and

Figures 6 and 7 represent the shell adjusting arm; Figure 6 being a perspective view of the complete arm; and Figure 7 a view of the blank from which it is made.

1 represents the timer shaft; 2 a fixed structure having an annular centering bead

2^a; and 3 the timer shell which is seated within the bead 2^a in order to hold the shell accurately in alinement with the axis of rotation of the timer. The centering portion 3^a of the timer shell is cylindrical to afford proper housing space for the terminals and contact device, and is connected through radial wall 3^b with the outer portion of the shell which is in the form of a dome 3^c that gives axial offset to the resilient retaining arm and centers its holding pressure with 55 relation to the cylindrical portion.

4 represents a resilient retaining arm usually employed in holding the shell of the timer in position, said arm in the present instance having at its free end a centering bead 70 4^a that seats in the depression 3^e in the apex of the dome, and thereby retains the arm in bearing against the shell 3 in holding the shell in position. 5 is the adjusting arm attached to the radial wall 3^b through which 75 the angular position of the terminals of the circuit closer are adjusted relatively to the cycle of the contact device in determining the time of ignition relative to the position of the engine pistons. Arm 5 is preferably 80 formed from the stamped blank 5^a (Figure 7) bent into the form of Figure 6 to provide the bearing loop 5^b to receive the connecting rod, and the ears 5^c by which the arm is attached.

Projecting inwardly from the cylindrical wall of the shell 3 is an annulus 6, made up of a body of insulating material with inset terminal plates 6^a of conducting material which are in electrical connection with binding posts 7, as shown in the sectional portion of Figure 2.

The post 7 is rigidly united to its terminal plate 6^a, besides fitting snugly in the fiber annulus 6, and this accurately centers the 95 post 7 in the enlarged opening 7^a so as to maintain air space between the post and the shell. Fiber washer 7^b and binding nuts 7^c complete the organization of this part of the structure.

8 represents the contact device which is constructed with a sleeve 8^a, through which it is mounted upon the shaft 1, and a sweep or arm 8^c projecting radially therefrom, this device being preferably constructed from a blank stamped from sheet metal, as suggested in Figure 4, with the arm 8^c projecting from the inner edge of one of two com-

plementary reduced portions 8^b, 8^{b'} which extend in opposite circumferential directions from the respective sides of a wide intermediate portion, so that the lapping of the reduced portions will complete the cylinder of the sleeve, and the arm, when deflected at right angles to the plane of the blank, will occupy a position radial to the sleeve at a point intermediate of its ends. The contact device thus completed is secured in position upon the shaft by the diametrical locking pin 9.

Upon the arm 8^c is mounted a contact shoe 10 having upturned ends to provide a sliding runner that will freely traverse the surface of the annulus 6. The slide shoe 10 is struck up from a plate of metal and centrally provided with an elongated or angular perforation 10^a through which it receives, with freedom of movement, the end of the arm 8^c. By substantially conforming the perforation to the section of the arm, the shoe is held in alinement with the annulus upon which it travels. The shoe is further provided with a depression 10^d to accommodate the washer or upset head by which it is confined on the arm. Spring 11, surrounding arm 8^c and abutting at one end against the sleeve 8^a and at its other end against the depressed portion 10^d of the shoe, constantly presses the slide shoe against the annulus 6. The shoe covers a length of arc sufficient to prevent tripping and develops a two point slide bearing with its bearing points spaced apart in direction of travel, while substantial conformity between perforation 10 and the section of arm 8^c retains the alinement of the shoe with the direction of travel.

The construction of the contact sleeve and arm from a blank, as described, and the particular construction of the shell are not herein claimed, but constitute features of my application, Serial No. 259,930, filed October 28, 1918.

I claim:

1. In a timer, an annulus carrying terminals, and a contact device cooperating with said annulus and comprising an arm and a slide shoe mounted to rock freely on said arm and bearing against said annulus; said slide shoe being curved to develop two contact areas spaced apart in the direction of the circumference of the annulus and with a depression between said areas; and said shoe being perforated in said depression and receiving the arm in its perforation.

2. In a rotary contact device for electric circuit timers, an arm mounted to travel about an axis of revolution, a slide shoe mounted transversely upon the end of said arm with limited movement longitudinally of the arm, and a spring carried by said arm pushing said slide shoe radially outward thereon; said shoe being constructed with an intermediate depressed portion through which it is received by the arm and upturned end portions spaced apart by said depressed portion.

3. In a rotary contact device for electric circuit timers, a slide shoe, and means for supporting said slide shoe in a path of revolution; said means comprising a radial arm upon which the slide shoe is mounted, and a hub integral with said arm for mounting the arm upon a shaft; said hub being in the form of a sleeve constructed with a wide portion and two complementary narrow portions extending circumferentially in opposite directions from said wide portion, and overlapping to complete the sleeve; and said arm being deflected from the inner edge of one of said reduced portions and thereby positioned intermediate of the ends in the finished blank.

Signed at Chicago, Illinois, this 14th day of July, 1920.

EDWARD F. BESSEY.
